UNITED STATES PATENT OFFICE.

GEORGE B. HOOPER, OF NEWARK, NEW JERSEY.

DESIGN FOR A SIDE DRAWER CASE AND DRAWER FOR A SEWING-MACHINE.

SPECIFICATION forming part of Design No. 14,216, dated August 21, 1883.

Application filed January 10, 1882. Renewed May 18, 1883. Term of patent 14 years.

To all whom it may concern:

Be it known that I, GEORGE B. HOOPER, a resident of Newark, in the county of Essex and State of New Jersey, have invented and produced a new and original Design for Side Drawer Cases and Drawers for Sewing-Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification, in which—

15 Figure 1 is a front view, and Fig. 2 a side elevation, of my newly-designed case with drawers therein; Fig. 3, a sectional view of a portion of the case; Fig. 4, a perspective view of a drawer; and Fig. 5, a sectional view of a front of a drawer, taken through line *x*.

Heretofore cases of drawers intended for sewing-machines have, as a rule, been made square or angular.

The leading feature of my design consists in 25 a case in which the sides present a scalloped or corrugated surface, while the front end of the drawers and the bottom of the case are round, or approximately so, as shown in Figs. 1, 2, and 4. The case *a* is provided with a 30 raised border molding, *b*, which is preferably flat, as shown, but may be done away with, if desired. The case is intended to depend from the sewing-machine table *c*, being secured by appropriate means from the under surface 35 thereof. The bottom of said case is therefore rounded, as shown, giving an extremely neat and appropriate finish to the case.

The fronts of the drawers correspond with 40 the general contour of the case, and the members of the ornament are therefore circular. The design I prefer for said drawer-front is shown more clearly in Figs. 1, 4, and 5, and is, first, a depressed center, *d*, in which is placed the knob *e*; second, a flat facing, *f*, surrounding the same, having a shoulder, *g*, forming its outer edge, and a bevel, *h*, all arranged 45 in the order given from the center outward.

The periphery of the drawer-fronts, instead 50 of being a continuous circle, may be cut straight, as shown in Fig. 1, which feature tends to increase the beauty of the design.

Should I so desire, I may form the bottom 55 of the drawer flat where the same comes in contact with the partitions *k*; but I prefer a continuously-curved outline for the same.

What I claim, and wish to secure by Letters Patent, is—

1. The design for a case of drawers for a sewing-machine, herein shown and described, the same consisting of the scalloped or corrugated sides, as set forth. 60

2. The design for a case of drawers, the same consisting in the scalloped or corrugated sides of the case and the rounded ends or fronts of the drawers, as set forth. 65

3. The design for a case of drawers, the same consisting in a case having scalloped or corrugated sides connected by a rounded bottom, the drawers therein having correspondingly-curved fronts, the edges of which, where 70 they approach a straight line, (such as the bottom of the table or an adjacent drawer,) are cut parallel to said line, all as herein set forth and shown.

4. The design for a depending drawer-case 75 for sewing-machines, the same consisting in a depending drawer-case having the sides thereof connected by a regularly-curved bottom.

5. The design for a drawer-front—to wit, a drawer-front having a circular recessed center 80 with a knob therein, a flat band or face surrounding said depressed center, a shoulder outwardly bordering said band, and a beveled outer fascia lying adjacent to the edge of the drawer-front. 85

6. The design for a case of drawers depending from a sewing-machine table—to wit, a depending case having curvilinear corrugated sides connected by a rounded lower extremity, the drawers in said case having fronts thereon, 90 the ornamental members of which are circular in outline when viewed from the front of said case, as shown and described.

7. The design for a drawer-case adapted to depend from a table—to wit, a depending 95 drawer-case having curvilinear corrugated sides and a rounded bottom, and having flat bands extending entirely around said sides and bottom at points thereon adjacent to the front and back edges thereof, as set forth and 100 shown.

In testimony that I claim the foregoing I have hereunto set my hand this 4th day of January, 1882.

GEORGE B. HOOPER.

Witnesses:

OLIVER DRAKE,

CHARLES H. PELL.
